UNITED STATES PATENT OFFICE.

HERMAN W. GLADITSCH, OF PORTLAND, OREGON.

SACK-FILLING MACHINE.

1,236,923.

Specification of Letters Patent. Patented Aug. 14, 1917.

Application filed June 12, 1916. Serial No. 103,356.

To all whom it may concern:

Be it known that I, HERMAN W. GLADITSCH, a citizen of the United States, and a resident of the city of Portland, county of 5 Multnomah, State of Oregon, have invented a certain new and useful Improvement in Sack-Filling Machines, of which the following is a specification.

My invention relates to machines for filling sacks, especially grain sacks.

The object of my invention is to provide an efficient machine operating to hold the sack, for filling, under the spout of the hopper, and simultaneously jiggling the sack so 15 as to cause the same to be compactly filled. It is also the object of my improved machine to eliminate any undue strain on the upper part of the sack, and to support the load contained therein on a support on which 20 the bottom of the sack rests at all times.

Furthermore, instead of vibrating only the bottom end of the sack, as is commonly done in machines of this character, I have so arranged my machine as to cause the sack 25 to be vertically oscillated or jiggled throughout its length, thereby promoting the compact filling of the same.

It is further my object to make my machine adjustable to sacks of varying sizes; 30 and it is also my object to make my machine of simple construction and operation.

The details of my invention are fully illustrated in the accompanying drawings, in which:

35 Figure 1 is a front elevation of my machine;

Fig. 2 is an enlarged fragmental sectional view taken approximately on the line 2—2 of Fig. 1;

40 Fig. 3 is a plan view of one of the vibrating platforms;

Fig. 4 is a plan view of the gear shift lever; and

Fig. 5 is an enlarged front elevation of 45 the devices which are adapted to support and hold open the mouth of a sack.

In the drawings I have shown my device adapted for filling grain sacks in a harvest field. For the purpose of convenience, the 50 device will be housed in a transportable framed structure adapted to be positioned near the threshing machine, from which the threshed grain is delivered. In such drawings the structure is shown in more or less 55 stripped form, but in actual use such structure will be provided with side curtains,

racks for holding empty sacks, and many other features which, while not possessing any patentable novelty, will add much to the utility and convenience of the machine. 60

The structure which is represented in its entirety by *a*, comprises a floor *b*, columns *c*, *d*, and a roof *e*. The floor is reinforced by the beams *f*, and the columns are cross-braced by steel angles *g*. A hopper *h* is 65 provided at its lower end with two spouts *i*, the delivery ends of which are parallel, and permit the machine to be built in two units. If desired, the hopper could be made with any number of spouts, so that the machine 70 could be built to a still larger capacity.

A slide valve *j*, provided with an operating handle *k*, is adapted to form a closure for the lower end of the hopper, so as to prevent any grain from being delivered to 75 the spouts when the machine is inactive.

The common throat between the spouts *i* and the hopper is provided with a pivoted valve diaphragm *l* and an operating lever *m*, said valve diaphragm being so positioned 80 that it will control the entrance to either of the spouts. In this way grain from the hopper may be directed down either spout, as desired, and prevent grain from being discharged through the other spout.

The hopper *h* is provided with a pair of transverse rigid bars *n*, the ends of which are secured to the slide rods *o*. The latter are mounted in bearings *p* fixed on the columns *d*, and said rods *o* are also connected by transverse frame members *q*. 85

The frame, of which said rods form elements, is adapted to be adjusted vertically with respect to the floor of the structure. The means by which the frame is adjusted 95 consists of the following parts: Parallel shafts *r* are rotatably mounted in bearings *s* fixed on the columns *d*. Sheaves *t* and sprockets *u* are fixed on these shafts and flexible connections *v* have their lower ends 100 secured to the frame members *q* and their upper ends secured to the sheaves *t*. In this way, when the sheaves *t* are rotated in the proper direction, by means of a crank handle attached to the squared end of one of the 105 shafts *r* (shown in Figs. 1 and 2) the flexible connections will be wound on the sheaves and the frame correspondingly elevated. A chain drive *w*, connecting the two sprockets *u*, cause the shafts *r* to rotate together in the 110 proper direction. The pawl and ratchet *x* will lock said shafts against rotation in any

one direction, and when said lock is released the frame will drop by gravity.

The rear slide rods *o* of the frame are connected by a rigid transverse shaft *y*.
5 Pivotally supported by the latter are the arms *z*, said arms being equal in number to the spouts of the machine. Each arm has rigidly mounted on its forward end a box-like member *3*, into which the lower end of
10 the spout projects. In view of the fact that the construction of these units is identical, only one will be described herein.

A sheave *4* is rotatably mounted in a bracket *5* which is bolted to a frame member *6* at the rear of the spouts. Brackets *7* are mounted on the rear columns *d* and support a transverse shaft *8*, on which is loosely mounted a sheave *9*, located in the same vertical plane as the sheave *4*. A flexible connection *10* has one end secured to the arm *z*, running thenceforth over the sheaves *4* and *9* and having its other end connected to a lever arm *11* (see Fig. 2) of the jigger element. The lever arm *11* is fulcrumed at *12* on a supporting member *13* and said lever has mounted on one end a cam roll *14*, the other end being formed with a yoke *15*. Pivotally supported at the ends of this yoke is a U-shaped sack-holding jigger support *16* on which the sacks *17* are placed. Said supports are provided with perforated end flanges *18*, which slide on the guide pins *19*, the latter being rigidly secured on the floor *b*. The bottom of these
35 sack holders is made with an opening *20*, and blocks *21*, mounted on the floor *b*, are adapted to relatively enter said openings when the sack holder is rocked in the position shown in Fig. 2. In this way the
40 middle portion of the bottom of the sack is vibrated so as to cause the material to be moved into and compactly fill said ends or corners.

The sack holder is adapted to be vibrated or jiggled at a high rate of speed, and will act so as to violently shake the sack so that the grain may be packed therein. The means for operating the jigger element consists of the following parts: A power shaft *22* is
45 rotatably mounted between the rear columns *d*. Said shaft has fixed on one end a pulley *23* adapted to be connected with a drive belt which is run either from the threshing machine, or from a separate
50 source of power not shown.

Slidably keyed on the shaft *22* are the bevel pinions *24*, connected by a shifting sleeve which is adapted to be moved longitudinally on said shaft by the operation of
60 a control lever *25*. The operating of this shifting mechanism is shown clearly in Figs. 2 and 4, and comprises the following parts: A shifter *26* is provided at its lower end with a yoke *27*, adapted to engage the
65 shifter sleeve. Said shifter is slotted at its

upper end, as indicated at *28*, and is pivoted at *29* in a transverse slotted supporting member *30*. The control lever *25* is provided with a slot *31* (see Fig. 4) through which extends a fulcrum pin *32*, securely supported by the hopper *h* midway between the two spouts *i*. The rear end of said control lever extends through the slotted end *28* of the shifter, and the handle end of the lever is supported on the transverse notched bar *33*, which is adapted to lock the lever so as to hold the gears *24* in either position to which they are shifted. Rotatably mounted in bearings beneath the shaft *22* are the divided shaft sections *34*,
70 the adjacent ends of which are mounted in a bearing on a center post *35*. Each of these shaft sections has fixed thereon a bevel friction gear *36*, and the shifting of the gears *24* will place either one of the shaft sections in driving state. Each section *34* has fixed thereon a cam *37* against which the cam roller *14* is adapted to bear, and when one of the shaft sections *34* is rotated, the cam will operate to jig the sack-holding element.
75

As a means for supporting the mouth of the sack, I have provided the device shown more clearly in Figs. 2 and 5, and which consists of the following parts: Shafts *40*
80 are rotatably mounted in bearings *41* on the front and rear faces of the box *3*. Said shafts have fixed on their outer ends the hook levers *42* one of which is provided with an arm *43*. Said levers are connected by reversing links *44* so that when the arm *43* is operated the device will move substantially as shown by dotted lines in Fig. 2. As a means for holding these devices
85 in any position to which adjusted, I provide an expansion spring brake *45*, shown in Fig. 5.
90

The general operation of my device is as follows: Threshed grain from the threshing machine is deposited into the hopper *h*,
110 either from a delivery spout or an elevator, not shown. A sack *17* is secured in position beneath one of the spouts *i* by placing the mouth of the sack around the box *3* (as shown in Fig. 2) and thereupon throwing the arm *43* to the position shown in broken lines in Fig. 2. This movement will cause the hooks of the levers *42* to engage the bag so as to hold its mouth fully open and in elevated position. The hopper *h* is then adjusted to the proper height so that the bag will be almost fully distended, its lower end being supported by the jigger element. The valve *l* is then operated so as to permit the grain to flow down through the spout to
115 which the bag is attached, and the gear shifting mechanism operated so as to place the corresponding shaft section *34* in driving state, whereupon the sack jigger will be actuated.
120 This operation is continuous, and an
125 130

operator can remove and sew a sack while another sack is being filled. It is to be noted that the sack is supported entirely at its lower end, so that no strain is placed on the 5 upper end of the sack.

In the jiggling operation, the jiggling element is first lifted by the cam, and then dropped by gravity, and during the last 10 movement the block 21 will relatively enter through the opening 20 and form an abutment against which the bottom of the sack will strike, thereby causing the grain to be more uniformly distributed and compacted in the sack. Furthermore, during the 15 actuation of the jigger member, the means for holding the upper end of the sack in open, uplifted position, will be caused to vibrate in synchronism with the jigger member, by means of the flexible element 10, as shown 20 in Fig. 2.

When a sack of different length is to be filled, the hopper is elevated by the means previously described, so that the mouth-holding means for the sack, and the sack-holding seat of the jigger, will be spaced 25 apart the desired amount.

I claim:

1. A sack filling machine comprising a 30 hopper provided with a discharge spout, vertically oscillable means for holding the upper end of said sack open about said spout,

a support for the bottom end of the sack consisting of a fixed part and a vertically oscillable part, and means for simultaneously operating said means holding the upper end of the sack and said oscillating part of the support for the bottom end of the sack. 35

2. A sack filling machine comprising a vertically adjustable hopper provided with a discharge spout, vertically oscillable means 40 for holding the upper end of said sack open about said spout, a support for the bottom end of the sack consisting of a fixed part and a vertically oscillable part, means for simultaneously operating said means holding the 45 upper end of the sack and said oscillating part of the support for the bottom end of the sack, and said oscillating means being adapted to accommodate the change in vertical position of said holding means for the 50 upper end of the sack.

3. A sack-filling machine comprising a hopper provided with a discharge spout, vertically oscillable means for holding the upper ends of the sack open about said spout, a 55 vertically oscillable support for the middle portion of the bottom end of the sack, and means for simultaneously operating said means holding the upper end of the sack and said oscillating support for the bottom end 60 of the sack.

HERMAN W. GLADITSCH.
